[57] CLAIM

The ornamental design for a sample cartridge, as shown and described.

DESCRIPTION

FIG. 1 is a top view of the sample cartridge, showing our new design;

FIG. 2 is a right side view of our design;

FIG. 3 is an end view of our design;

FIG. 4 is a left side view of our design;

FIG. 5 is an exploded view of our design;

FIG. 6 is a bottom view of our design; and,

FIG. 7 is a view of our design toward an opposite end from that shown in FIG. 3.

The following do not form part of the claimed design: the broken line depiction of a needle cap; and the inside surfaces which are not shown in the drawings.

1 Claim, 3 Drawing Sheets

FIG. 1***FIG. 2******FIG. 3***

FIG. 4

FIG. 6

FIG. 7
